UNITED STATES PATENT OFFICE

110,527

DESIGN FOR A STRAIN TESTING INSTRUMENT

Arne J. Oker, Southbridge, Mass., assignor to
American Optical Company, Southbridge,
Mass., a voluntary association of Massachu-
sets

Application March 31, 1938, Serial No. 76,210

Term of patent 14 years

To all whom it may concern:

Be it known that I, Arne J. Oker, a citizen of the United States, residing at Southbridge, in the county of Worcester and State of Massachusetts, have invented a new, original, and ornamental Design for Strain Testing Instruments, of which the following is a specification, reference being made to the accompanying drawing forming a part thereof.

Fig. I is a perspective view of a strain testing instrument embodying my design;

Fig. II is a front view of the device shown in Fig. I; and

Fig. III is a side view of the device shown in Figs. I and II.

The characteristic features of my design com-

prise broadly a base having smooth outer contour surfaces with a top inclined toward the front of said base and supporting an annular shape member and having a relatively slender upright support extending upwardly from adjacent said annular member and turning forwardly with an arched curve and having a relatively small annular shaped member adjacent the end thereof in substantial alignment with the first annular member in a direction substantially normal to the plane of the top.

I claim:

The ornamental design for a strain testing instrument substantially as shown and described.

ARNE J. OKER.
